US00D732068S

(12) **United States Design Patent**
Tsaur et al.

(10) **Patent No.:** **US D732,068 S**
(45) **Date of Patent:** **** Jun. 16, 2015**

(54) **DISPLAY DEVICE WITH GRAPHICAL USER INTERFACE**

(71) Applicant: **Symantec Corporation**, Mountain View, CA (US)

(72) Inventors: **Ynn-Pyng Tsaur**, Oviedo, FL (US); **Baishen Zhu**, Sanford, FL (US); **Lijo Abraham**, Lake Mary, FL (US); **Gregory Robert Dowers, II**, Lake Mary, FL (US); **Kirk Freiheit**, Lake Mary, FL (US)

(73) Assignee: **Symantec Corporation**, Mountain View, CA (US)

(**) Term: **14 Years**

(21) Appl. No.: **29/439,714**

(22) Filed: **Dec. 13, 2012**

(51) **LOC (10) Cl.** **14-04**

(52) **U.S. Cl.**

USPC **D14/488**

(58) **Field of Classification Search**

USPC **D14/485-495**

CPC **G06F 3/048; G06F 3/0481; G06F 3/0482; G06F 3/04817**

See application file for complete search history.

(57) **CLAIM**

The ornamental design for a display device with a graphical user interface, as shown and described.

DESCRIPTION

The FIGURE is a front view of a graphical user interface for a display device showing the claimed design. The broken lines shown in the FIGURE illustrate portions of the graphical user interface and a display device that form no part of the claimed design.

1 Claim, 1 Drawing Sheet
